THERAPEUTIC CONTAINER FOR ICE WATER AND THE LIKE

Sidney R. Witz, 340 N. Mansfield Ave.,
Los Angeles, Calif.

Filed Feb. 23, 1961, Ser. No. 64,024

Term of patent 3½ years

(Cl. D83—1)

Fig. 1

Fig. 2

Fig. 3

FIGURE 1 is a top perspective view of a therapeutic container for ice water and the like embodying my new design;

I claim:

The ornamental design for a therapeutic container for ice water and the like as shown.
